United States Patent Office

Des. 206,974
Patented Feb. 14, 1967

206,974

BOAT HULL

Charles W. Sherburne, 3409 S. Patton Ave.,
San Pedro, Calif. 90731

Filed Dec. 20, 1965, Ser. No. 249

Term of patent 14 years

(Cl. D71—1)

FIG. 1 is a top plan view of a boat hull showing my new design;

FIG. 2 is a bottom plan view thereof;

FIG. 3 is a front side elevational view thereof, the rear side elevational view thereof, being identical, is omitted for brevity;

FIG. 4 is a left end elevational view thereof; and

FIG. 5 is a right end elevational view thereof.

I claim:

The ornamental design for a boat hull, substantially as shown and described.
